ELECTROPLATING APPARATUS

Delbert G. Van Ornum, Great Falls, Mont.

Application January 23, 1946, Serial No. 642,921

4 Claims. (Cl. 204—224)

1

The present invention relates to new and useful improvements in electroplating apparatus and more particularly to a machine for accurately building up to exact dimensions various types of metal surfaces, such as shafts, internal or external cylinder walls, or flat surfaces by means of an electrode mounted for movement over the work and maintained in slightly spaced relation from the work while an electroplating solution bridges the space between the work and the electrode.

An important object of the invention is to provide a yieldable mounting for the electrode embodying spring means for holding the electrode in closely spaced relation with respect to the work and an electric switch operable to open a circuit connected to the electrode upon a building-up of the surface of the work to a predetermined thickness through a movement of the electrode by the building action.

A further object of the invention is to provide a device of this character adapted for operation while immersed in the electroplating solution, or in which the solution may be applied to the contacting end of the electrode and confined between the electrode and the surface of the work during the electroplating action.

A still further object is to provide a device of this character of simple and practical construction, which is efficient and reliable in operation, relatively inexpensive to manufacture and otherwise well adapted for the purposes for which the same is intended.

Other objects and advantages reside in the details of construction and operation as more fully hereinafter described and claimed, reference being had to the accompanying drawings forming part hereof, wherein like numerals refer to like parts throughout, and in which:

Figure 1 is a perspective view.

Figure 2 is an enlarged plan view of the switch with the cover plate for the switch housing removed.

Figure 3 is a fragmentary longitudinal sectional view of the contacting end of the electrode.

Figure 4 is a transverse sectional view taken on a line 4—4 of Figure 2.

Figure 5 is an enlarged bottom plan view of the rear end of the electrode with the cover plate for the electrode housing removed.

Figure 6 is an enlarged longitudinal sectional view through the switch housing.

Figure 7 is a fragmentary side elevational view of the contacting end of the electrode showing

2

an applicator attached thereto for the electroplating solution, and

Figure 8 is a perspective view of the switch-operating arm.

Referring now to the drawings in detail and first with respect to the form of invention illustrated in Figures 1 to 6 inclusive the numeral 5 designates an elongated substantially flat housing of insulation material having its bottom surface formed with a longitudinally extending channel or groove 6 open at one end of the housing and having an electrode in the form of a bar 7 slidably mounted therein.

The electrode 7 is projected forwardly at the front end of the housing 5 by means of a coil spring 8 positioned against the rear end of the electrode at the channel 6, the spring forming a conductor between the electrode and a terminal 9 extending outwardly through the top of the housing 5 and designed to be connected in an electric circuit in a manner and for a purpose presently clear.

The front outer end of the electrode 7 is bifurcated as shown at 10 and in which is rotatably mounted an insulation non-conducting disk 11 by means of a pin or rivet 12 and also rotatably mounted on the pin 12 at one side of the disk 11 is a disk 13 of conductive material and of a diameter less than the disk 11 as shown to advantage in Figure 3 of the drawings.

One edge of the electrode 7 is formed with rack teeth 14 engaging a pinion 15 secured to the lower end of a shaft 16 journaled in the housing 5 and projecting upwardly therefrom into a liquid-tight switch housing 17 secured on top of the housing 5. An arm 18 is positioned in the switch housing and secured to the upper end of the shaft 16 for swinging the arm in one direction in accordance with a predetermined inward sliding movement of the electrode 7.

The arm 18 is of non-conductive material and engages one side of a resilient switch arm 19 of conductive material which has one end anchored in a split post 20 of non-conductive material rising in the housing 17. The free end of the switch arm 19 is provided with a breaker point 21 adapted for movement into and out of engagement with a stationary breaker point 22, the switch arm and the breaker point 22 having circuit wires 23 and 24 connected thereto and extending outwardly through adjacent ends of the housing 17 for a purpose presently seen. The switch housing 17 is closed by a liquid-tight cover plate 25. The housing 5 is designed to be partly immersed, that is, to the housing 17, in an electroplating solution

with the insulation disk 11 positioned to travel against the surface of work also immersed in the solution and the housing 5 and electrode 7 are designed to be moved in a fixed path to travel along the surface of the work, by fixing the housing 5 in a lathe, or the like, not shown. The insulation disk 11 is held against the surface of the work by the spring 8 which projects the electrode 7 outwardly of the housing 5 thereby releasing the switch arm 19 to close the breaker points 21 and 22.

The electrode 7 is designed to be interposed in a suitable electric circuit, a diagrammatic representation of which has been shown in Figure 1 with a battery 13 representing the source of electrical energy and grounded as at 32 with a line 33 to one side 34 of a spring opened solenoidac switch 35 remote from the device and outside of the solution, said line 33 having a control switch 36 therein. The other side 37 of said switch 35 is connected by a line 38 to the terminal 9 of the electrode 7. The wire 23 branches from the line 33 and the wire 24 extends to one side of the solenoid 39 of said switch 35 and which is grounded as at 40 to be energized when the breaker points 21, 22 are closed and thereby operate the core 41 to close said switch 35.

The device is moved, as by the means previously mentioned, over the work, as shown for instance at 29, to be electroplated and the electrode 7 is normally extended outwardly of the housing 5 by the spring 8 so that the breaker points 21, 22 are closed. Therefore, with the switch 36 closed, the solenoid 39 will be energized to maintain the solenoidac switch 35 closed and the electrode 7 will be energized. As the surface of the work 29, over which the disks 11 and 13 travel, is built up, the electrode 7 will be shoved inwardly of the housing 5 until a predetermined thickness of electroplating is attained, whereupon, the arm 18 will be actuated by the rack 14 and pinion 15 to move the switch arm 19 to separate the breaker points 21, 22, whereupon, the solenoid 39 will be deenergized to permit the solenoidac switch 35 to open and thereby deenergize the electrode 7, in a manner which will be clear.

As will be understood, when the breaker points 21, 22 are closed, or engaged, and the solenoidac switch 35 closed, electric current will flow through the electrode 7 and solution, not shown, whereby the work 29, as shown, will be electroplated according to the usual well known process, and when the electrode 7 is deenergized, in the manner described in the foregoing, the electroplating process will be stopped.

In Figure 7, I have illustrated a modified form of the invention which comprises a tube 26 secured to the outer end of the electrode 1a by a bracket 27 and attached to the discharge end of the tube is a wick 28 positioned beneath the tube and wiping against the work 29, immediately above the conductor disk 13a and non-conductive disk 11, the tube being adapted to supply electroplating solution to the wick for action thereon by the electrode to electroplate the surface of the work.

In view of the foregoing description taken in conjunction with the accompanying drawings it is believed that a clear understanding of the construction, operation and advantages of the device will be quite apparent to those skilled in this art. A more detailed description is accordingly deemed unnecessary.

It is to be understood, however, that even though there is herein shown and described a

preferred embodiment of the invention the same is susceptible to certain changes fully comprehended by the spirit of the invention as herein described and the scope of the appended claims.

Having thus described the invention, what is claimed as new is:

1. An electroplating device comprising a housing of non-conductive material and adapted to be moved in a fixed path over a piece of work to be electroplated, an electrode projecting out of said housing to travel therewith with one end in close proximity to the work, said electrode being slidably mounted in said housing for retraction therein, work-engaging means of insulation material secured to and extending beyond said electrode for causing retraction of the electrode into said housing as the thickness of the electroplating on the work increases, a switch carried by said housing for controlling an electric circuit in which the electrode is interposed, and means for opening said switch operative by retraction of said electrode in a predetermined degree.

2. An electroplating device comprising a housing of non-conductive material and adapted to be moved in a fixed path over a piece of work to be electroplated, an electrode projecting out of said housing to travel therewith with one end in close proximity to the work, said electrode being slidably mounted in said housing for retraction therein, work-engaging means of insulation material secured to and extending beyond said electrode for causing retraction of the electrode into said housing as the thickness of the electroplating on the work increases, a switch carried by said housing for controlling an electric circuit in which the electrode is interposed, means for opening said switch operative by retraction of said electrode in a predetermined degree, a terminal on said housing adapted to be interposed in said circuit, and spring means for opposing retraction of said electrode and forming an electrical conductor between said electrode and terminal.

3. An electroplating device comprising a housing of non-conductive material and adapted to be moved in a fixed path over a piece of work to be electroplated, an electrode projecting out of said housing to travel therewith with one end in close proximity to the work, said electrode being slidably mounted in said housing for retraction therein, work-engaging means of insulation material secured to and extending beyond said electrode for causing retraction of the electrode into said housing as the thickness of the electroplating on the work increases, a switch carried by said housing for controlling an electric circuit in which the electrode is interposed, means for opening said switch operative by retraction of said electrode in a predetermined degree including a rack and pinion, and a switch opening arm swingable by operation of said pinion.

4. An electroplating device comprising a housing of non-conductive material and adapted to be moved in a fixed path over a piece of work to be electroplated, an electrode projecting out of said housing to travel therewith with one end in close proximity to the work, said electrode being slidably mounted in said housing for retraction therein, work-engaging means of insulation material secured to and extending beyond said electrode for causing retraction of the electrode into said housing as the thickness of the electroplating on the work increases, a switch carried by said housing for controlling an electric circuit

in which the electrode is interposed, means for opening said switch operative by retraction of said electrode in a predetermined degree, and means on said electrode for supplying electroplating solution between said electrode and the work.
